UNITED STATES PATENT OFFICE.

EUGENE S. CALDWELL, OF PHILADELPHIA, PENNSYLVANIA.

DESIGN FOR A THERMOSTATIC VALVE.

42,081.

Specification for Design.

Patented Jan. 9, 1912.

Application filed September 25, 1911. Serial No. 651,297. Term of patent 14 years.

To all whom it may concern:

Be it known that I, EUGENE S. CALDWELL, a citizen of the United States, residing at Philadelphia, county of Philadelphia, and State of Pennsylvania, have invented a new, original, and ornamental Design for Thermostatic Valves, of which the following is a specification, reference being had to the accompanying drawings, forming part hereof, in which—

Figure 1 is a front elevation, and Fig. 2 is a top or plan view of a thermostatic valve embodying my design.

What I claim is:

The ornamental design for a thermostatic valve, as shown.

EUGENE S. CALDWELL.
